T. A. MAXWELL,
HAIR CUTTING DEVICE,
APPLICATION FILED APR. 17, 1919.

1,353,173.

Patented Sept. 21, 1920.

UNITED STATES PATENT OFFICE.

THOMAS A. MAXWELL, OF CHANUTE, KANSAS.

HAIR-CUTTING DEVICE.

1,353,173.

Specification of Letters Patent. Patented Sept. 21, 1920.

Application filed April 17, 1919. Serial No. 290,774.

To all whom it may concern:

Be it known that I, THOMAS A. MAXWELL, a citizen of the United States, residing at Chanute, in the county of Neosho and State 5 of Kansas, have invented certain new and useful Improvements in Hair-Cutting Devices, of which the following is a specification.

This invention relates to an improved 10 hair cutting device for use in cutting hair in a style generally known as bobbing or as a "Buster Brown" hair cut and the principal object of the invention is to provide a hair cutter so constructed that it may be placed upon the head and supported thereon 15 with the hair extending in operative relation to the cutting piece and clamped in position so that the hair may be cut evenly and prevented from getting out of position 20 while being cut.

Another object of the invention is to so construct this hair cutter that the cutting blades may be guided in their movement and held in proper contact so that the hair will 25 not be caught and pulled when being cut and to further so mount these blades that they may be taken apart for sharpening.

Another object of the invention is to so construct this hair cutter that the supporting 30 rods may be adjusted according to the size of the head and according to the point at which it is desired to have the hair cut.

Another object of the invention is to so construct this hair cutter that it will be easy 35 to operate.

This invention is illustrated in the accompanying drawings wherein—

Figure 1 is a view showing the improved 40 hair cutter in plan, a portion of the handles being broken away to show the means for mounting a spring yieldably holding the handles in a set position,

Fig. 2 is a view showing the improved hair 45 cutter in elevation with the supporting rods removed,

Fig. 3 is a plan view of the improved hair cutter looking from the opposite side from that shown in Fig. 1,

Fig. 4 is an enlarged fragmentary view 50 showing the manner of connecting the handles with the blade, and,

Fig. 5 is a fragmentary sectional view 55 through the hair cutter at the point where the clamp is pivotally mounted.

This improved hair cutter is provided with the upper and lower blades 10 and 11,

the upper blade being provided with longitudinally extending slots 12 and the lower blade with pins 13 which extend through the slot 12 and carry securing nuts 14 for 60 engaging the upper blade and holding the upper blade in proper engagement with the lower blade. It should be noted that by proper adjustment of these nuts 14 the blades may be permitted to slide without 65 binding and at the same time without being so loosely connected that there would be danger of the hair becoming caught between the blades and thus pulled instead of being cut by the cutting teeth formed along 70 the outer edge portion of the blade. A plate 15 which resembles a comb and constitutes a guide is secured to the inner edge face of the lower blade 11 and extends upwardly 75 above the upper blade as shown in Figs. 2 and 4 so that its teeth may engage the hair to be cut thus guiding the hair across the cutter.

This hair cutter is provided with handles 80 16 and 17 which are positioned beneath the cutting blade and are provided at their inner or forward ends with fingers 18 and 19 connected with the inner edge portion of the blades and thus held rigidly in connection with the blades. These handles are 85 provided respectively with a tubular sleeve 20 and a finger or pin 21 which fits into the sleeve 20 and engages the spring 22 so that the handles will be yieldably held in the set position shown. The guiding plate 15 is cut 90 away about the connection for the handles so that when the handles are pressed for movement toward each other the blades may move thus causing the teeth at the outer edges of the blades to move in crossing relation for 95 cutting the hair. In order to hold the hair in proper position there has been provided a clamping strip 23 pivotally mounted at one end and swinging beneath the lower blade into operative position. This clamping strip is provided with teeth along its inner edge portion so that it will engage 100 the hair and firmly hold the hair in position for cutting.

In order to hold the hair cutter in place 105 upon the head while cutting the hair there has been provided a supporting structure including the sleeves 24 and 25 and rods 26 and 27, the sleeves and rods being connected with the lower blade or with the guiding plate. These rods 26 and 27 will be formed 110 of wire which will be flexible and pref-

erably resilient so that the wires may be drawn out of the tubes 24 and 25 when adjusting the clipper upon the head. If desired the sleeves may also be formed flexible so that they can conform to the contour of the head. It will thus be seen that when in use this cutter or clipper will fit securely upon the head and the cutting blades will be positioned about the back of the head adjacent the neck at a point where it is desired to have the hair cut.

When in use the hair will be combed out straight and the cutter will then be put in place with the supporting structure fitting about the head and hair, the clamping blade at this time of course being left in an extended position to one side of the cutting blade. The hair will now be carried over the cutting blade between the arms of the supporting structure and across the guiding plate and then carried downwardly and combed straight so that the hair passes between the teeth of the guiding plate 15 and down across the cutting blades. The clamping strip will then be swung into place and the hair will be securely clamped across the cutting teeth of the blades. The blades can now be moved through the medium of the handles and movement of the handles will cause the upper blade to reciprocate upon the lower blade and thus cause the hair to be cut evenly. It will thus be seen that with this device the hair can be easily and quickly cut and cut in a straight line about the head thereby permitting the hair to be cut in the desired manner rapidly and with a small amount of labor. It often happens that in bobbing hair and using scissors to cut the hair it is difficult to keep the hair an even length and it is to permit this object to be easily accomplished that the improved hair cutter has been developed. When it is desired to sharpen the blades or to take the device apart for cleaning or for repairs it is simply necessary to remove the securing nuts 14 thus releasing the blades and permitting them to be taken apart. I have therefore provided a very efficient device of the character described.

What is claimed is:

1. A hair cutting device comprising cutting means curved to substantially conform to the curvature of a portion of a head, means for operating the cutting means and means extending over the head for supporting the cutting means in position. 50

2. A hair cutting device comprising relatively movable cutter plates curved to substantially conform to the curvature of a head, means connected with cutter plates for moving the same to cut hair, means for supporting hair in position for cutting with reference to said cutter plates, means for holding the hair in engagement therewith, and adjustable members extending over the head 60 and carried by the cutter plates for the purpose set forth. 65

3. A hair cutting device comprising superposed relatively movable cutter plates curved to substantially conform to the curvature of a head, handles connected with the cutter plates for moving the same to cut hair, teeth for supporting hair in position for cutting with reference to said cutter plates, a clamping strip conforming to the curvature of the 70 cutter plates for holding the hair in engagement therewith, and an adjustable supporting member extending over the head and carried by the cutter plates for the purpose set forth. 75

4. A hair cutting device comprising superposed relatively movable cutter plates curved to substantially conform to the curvature of a head, teeth on the cutter plates, handles connected with the cutter plates for moving 85 the same to cut hair, teeth for supporting hair in position for cutting with reference to the teeth of said cutter plates, a clamping strip conforming to the curvature of the cutter plates for holding the hair in engagement with the teeth to insure the same being cut, and adjustable supporting members extending over the head and carried by the cutter plates for the purpose set forth. 90

In testimony whereof, I affix my signature 95 hereto.

THOMAS A. MAXWELL.
